UNITED STATES PATENT OFFICE.

JOHN CARLSON, OF MANDAN, NORTH DAKOTA.

ACETYLENE-GAS GENERATOR.

SPECIFICATION forming part of Letters Patent No. 623,132, dated April 18, 1899.

Application filed February 12, 1898. Serial No. 670,098. (No model.)

To all whom it may concern:

Be it known that I, JOHN CARLSON, of Mandan, in the county of Morton and State of North Dakota, have invented a new and Improved Acetylene-Gas Machine, of which the following is a full, clear, and exact description.

My invention relates to an improvement in acetylene-gas machines of that class in which the water is delivered in regulated amounts to the carbid for the generation of the gas.

The invention consists of certain novel features of construction, which will be herein-after described and claimed.

Reference is to be had to the accompanying drawings, forming a part of this specification, in which similar characters of reference indicate corresponding parts in all the figures.

Figure 1 is a top plan view of my device. Fig. 2 is a side elevation thereof. Fig. 3 is a sectional side elevation thereof on the line 3 3 in Fig. 1. Fig. 4 is a sectional plan view thereof on the line 4 4 of Fig. 3. Fig. 5 is a partial sectional elevation on the line 5 5 in Fig. 4. Fig. 6 is a sectional elevation of the relief-valve placed at the top of the condenser. Fig. 7 shows the spider used to hold the removable head in its place. Fig. 8 is a section showing the cut-off valve by which connection may be broken by hand between the water-supply and carbid-holder, and Fig. 9 is a perspective view showing one of the carbid-holders removed from the machine.

In my machine I make use of the ordinary bell-gasometer, with a water seal, which consists, essentially, of two hollow cylinders open at one end and placed one within the other in inverted positions, with water in the lower outer cylinder. This outer cylinder A, which forms one portion of the gasometer, has its outer shell extended below the partition a, which forms the bottom of the water-tank. In the lower chamber formed by the partition a is constructed a cylindrical chamber D, adapted to receive the carbid-holder. For convenience this chamber is constructed in cylindrical form, although the cylindrical shape is in no sense essential. This chamber D is connected by a pipe G with the interior of the outer portion A of the gasometer, within which is placed the water which forms the seal. Within the water-tank thus

formed is placed a valve H, closed by means of a lever H', provided at one end with a weight h, adapted normally to hold the valve closed. The cylinder A, which forms the outer portion of the gasometer and the water-tank, is supplied with sufficient water to keep the valve H immersed at all times. When the valve H is opened, water will flow through the pipe G and into the chamber D through the sprinkler-pipes g, which serve to scatter the water in the chamber. Within the chamber D is placed a carbid-holder E, formed as a cylinder having one side open. One end of the chamber D is extended beyond the outer casing A and is provided with an outwardly-extending flange a', and this end of the chamber is closed by a removable head d. The head d is placed over the open end of the cylinder, with suitable packing material between the head and the flange a', and is clamped in position by means of a spider F, preferably made of three radial arms, two of which are provided with hooks F', adapted to engage the rear edge of the flange a', and the third is straight, entering beneath the loop or staple f'.

Pressure is applied between the spider F and the head d by means of a hand-screw f, which passes through the spider and bears upon the head d. It is intended that at least two of these carbid-holders be provided for each machine, one of the holders to be filled before the other holder is removed from the machine, and the holder which has been removed is replaced by the filled holder.

The pipe G, connecting the water-tank with the chamber D, is provided with a valve G', by which the flow of water may be stopped. A pipe G² connects this valve with the outer casing, and through said pipe extends a rod G³, connected to the valve G' and provided at its outer end with a handle by which it may be turned by hand. When it is desired to remove one of the carbid-holders, the valve G' is closed, thus cutting off the supply of water. The gas which has been generated in the holder E escapes into the gasometer through a pipe D', provided at its upper end with an automatic closing-valve D², which will close and prevent any backflow of the gas.

The bell B, forming the movable part of the

gasometer, is provided with a central upwardly-extending rod B', which slides through a hole formed in the outer end of an arm I', extending horizontally from a post I, secured 5 to the outer casing A, and this arm I' serves to guide the gasometer in its rise and fall. The lower portion of the bell is provided with a loop b, extending about the pipe D' and serving to prevent rotation of the bell. The 10 bell is also provided with an inwardly-extending arm K, pivoted to the side of the bell, so that it may swing upward but not downward below a horizontal position. The inner end of this arm extends to the center of the bell 15 and is made of such weight that it will, when it comes in contact with the lever H', open the valve H to admit water to the carbid-holder. As soon as the water has been admitted through the valve H to the carbid-holder generation of gas commences. As soon 20 as this generation of gas is in excess of the consumption the bell B will rise, and thus permit the valve H to close until it has been again opened by the descent of the bell.

25 The gas is drawn from the gasometer by means of a pipe C', which extends upwardly through the partition a and also laterally through the outer casing, and there connects with the condenser C. This condenser consists of a cylinder secured to the outer casing A and receiving the gas from the gasometer. The gas is drawn off from the condenser near its upper end through the pipe C³. To the upper end of the condenser is attached a relief- 30 valve J, provided with a pivoted lever J', said lever being weighted, so as to normally hold the valve closed. This weight will be such that the valve will be held closed against any pressure at which it is desired to operate the 35 machine, but will be opened by any increase in pressure. The lever J' is also extended toward the gasometer, so that when the bell B rises above a certain height it will engage the lever and lift the valve J, thus allowing 40 the gas to escape and the bell to drop. This is a precaution to prevent the bell from being raised too high or the gasometer from being filled with gas under a greater pressure than normal.

45 For convenience in determining the height of water within the gasometer a glass tube A' is mounted alongside the outer casing and connected at its lower end to the outer casing A in the manner of an ordinary gage-glass. The tube at its upper end is provided with a funnel through which water may be poured to maintain the supply at such level as desired.

Having thus fully described my invention, 50 I claim as new and desire to secure by Letters Patent—

55 1. An acetylene-gas machine comprising a generator, a gasometer consisting of a bell adapted to float in a water-tank, a valve-controlled pipe connecting the water-tank with the generator, a lever normally holding said valve closed and an arm pivoted upon the

bell and adapted to engage the lever to open the valve when the bell descends, substantially as described.

70 2. An acetylene-gas machine comprising a generator having a removable head, a removable carbide-receiver adapted to be inserted in the generator, a gasometer consisting of a water-tank and a bell adapted to float in said tank, a valve-controlled pipe connecting the water-tank with the generator, a lever normally holding said valve closed, an arm pivoted upon the bell and adapted to engage the lever when the bell descends to open the valve, 80 a condenser connected with the gasometer and receiving gas therefrom, and a valve connected with the said condenser and opened by the rising bell, substantially as described.

85 3. In an acetylene-gas machine, a generator having a removable head adapted to be secured thereto by a gas-tight joint, a gasometer comprising a bell and a water-tank in which said bell is adapted to float, gravity-feed connections from the water-tank to the generator and including therein a normally-closed valve, a lever connected to said valve to open the same by the depression of one end of the lever, and a weighted arm upon the bell arranged to swing upward but normally 90 held in a horizontal position, the said arm being adapted to engage the lever to open the valve when the bell descends, substantially as described.

95 4. An acetylene-gas machine comprising a generator, a gasometer consisting of a bell and a water-tank in which said bell is adapted to float, a pipe connecting the water-tank with the generator and provided with a normally-closed valve, an arm connected with the bell 100 for opening said valve when the bell descends, a pipe leading from the generator to the upper part of the gasometer and provided at its upper end with an automatic closing-valve to prevent backflow of the gas, and a loop on 105 the lower part of the bell and through which the said pipe extends, substantially as described.

110 5. An acetylene-gas machine, comprising a generator having a removable head, a gasometer comprising a bell floating in a water-tank, a feed-pipe leading from the water-tank to the generator and provided with sprinkling-pipes to scatter the water in the generator, a normally-closed valve connected with the 115 feed-pipe and adapted when opened to admit water to the generator, a lever connected to said valve to open the same by the depression of one end of the lever, and a weighted arm upon the bell arranged to swing upward, but 120 normally held in a horizontal position, the said arm being adapted to engage the lever to open the valve when the bell descends, substantially as described.

125 6. An acetylene-gas machine comprising a 130 generator having a removable head, a removable carbide-receiver adapted to be inserted in the generator, a bell, a water-tank in which said bell is adapted to float, a feed-pipe con-

necting the water-tank with the generator and provided with sprinkling-pipes to scatter the water in the generator, a normally-closed automatic valve connected with the feed-pipe, a lever connected to said valve to open the same by the depression of one end of the lever, a weighted arm upon the bell arranged to swing upward but normally held in a horizontal position, the said arm being adapted to engage the lever to open the valve when the bell descends, a pipe leading from the generator to

the gasometer and provided at its upper end with an automatic closing-valve to prevent backflow of the gas, and a hand-operated valve also connected with the feed-pipe and adapted to be operated from the outside of the apparatus to cut off the supply of water, to the generator, substantially as described.
